WATER PUMP PLANTER

Gabriel Lopez, 4352 W. Belden, Chicago, Ill. 60639

Filed Sept. 22, 1975, Ser. No. 615,226

Term of patent 14 years

Int. Cl. D11—02

U.S. Cl. D35—3 B

FIG.1

FIG.2

FIG.3

FIG.4

FIG.5

FIG. 1 is a perspective view of a water pump planter showing my new design;

FIG. 2 is a front elevation thereof;

FIG. 3 is a side elevation thereof;

FIG. 4 is an elevation as seen from the side opposite FIG. 3; and

FIG. 5 is a top plan view thereof.

I claim:

The ornamental design for a water pump planter, as shown.
